UNITED STATES PATENT OFFICE.

GEORGE R. PIMLOTT, OF CHICAGO, ILLINOIS, ASSIGNOR OF ONE-HALF TO
WILLIAM G. RICE, OF HOUGHTON, MICHIGAN.

GUARD FOR FLEXIBLE CONDUCTORS.

SPECIFICATION forming part of Letters Patent No. 734,090, dated July 21, 1903.

Application filed June 25, 1902. Serial No. 113,114. (No model.)

To all whom it may concern:

Be it known that I, GEORGE R. PIMLOTT, a citizen of the United States of America, and a resident of Chicago, in the county of Cook and State of Illinois, have invented certain new and useful Improvements in Guards for Flexible Conductors, of which the following is a specification.

The main object of my invention is to provide an improved, simple, and inexpensive form of guard suitable for preventing flexible electric conductors from being abruptly bent or kinked and from having the insulation ruptured at the point of their connection with electric-light sockets or other fixtures where such conductors are liable to be similarly strained or bent. I accomplish this object by the device shown in the accompanying drawings, in which—

Figure 1 is an elevation, partly broken away, of an electric-light socket having a guard constructed according to my invention secured thereto. Fig. 2 is a bottom plan of the guard shown in Fig. 1 removed from the socket.

The device shown consists of an ordinary Edison socket 2, having the usual flexible conductor-cord 3 extending into the upper end of same and provided with a guard. The guard 4 consists of a screw-threaded nipple 5, fitting the threaded aperture 6 in the sleeve 7 at the upper end of the socket 2. The nipple 5 is provided with an annular shoulder 8 near its upper end, and the part 9 of the nipple 5 above the shoulder 8 is spun over the lower edge 10 of the member 11, which forms the main body part of the guard. The member 11 is preferably made of thin metal spun to substantially the form shown. The lower end of the member 11 is turned inwardly and upwardly and is firmly held between the shoulder 8 and the spun-over part 9 of the nipple 5. Since the lower edge of the member 11 is turned upwardly, an annular pocket 12 is formed in the lower part of the member

11 and below the upper end of the nipple 5. The lower wall of this pocket is provided with apertures 14, which conduct away water which may have accidentally entered the opening 13 at the upper end of the member 11 and prevent said water from accumulating in places where it would have contact with

the conductor-cord 3 or from entering the socket 2. The upper end 16 of the member 11 is flared outwardly and turned back upon itself with an easy curvature and serves as a 55 guide to the bending of the conductor-cord 3 at this point, thereby preventing the conductor-cord 3 from being sharply bent when it is pulled at an angle to the socket. The curvature of the guard shown is such that 60 the inner curve of the conductor-cord when said cord is turned at right angles to its normal position has a radius equal to more than double the diameter of the cord. This insures such gradual curve of the cord as will 65 prevent breaking at this point. The interior surface of the nipple 5 is preferably lined with a layer of insulating material 17.

The operation of the device will be apparent from the foregoing description. It will 70 be seen that the surface 18 of the member 11 will guide and ease the bending of the conductor-cord 3, and thereby prevent the kinking and chafing and the consequent rapid wear which occurs when the conductor is not 75 protected at its point of junction with the socket, as has been the practice heretofore.

It will be seen that numerous details of the construction shown may be altered without departing from the spirit of my invention. 80 I therefore do not confine myself to such details, except as hereinafter limited in the claims.

What I claim as my invention, and desire to secure by Letters Patent, is— 85

1. The combination of an electric-light socket having a flexible conductor secured thereto; a guard secured to said socket and surrounding said conductor, said guard being suitably flared and curved at its upper 90 part to prevent said conductor from being abruptly bent near its junction with said socket and having a pocket below the point where said conductor joins said socket, substantially as described. 95

2. An electric fixture, comprising a flexible conductor-cord, an electric-light socket secured to and suspended therefrom and having a tubular part forming a guard for the conductor-cord, said tubular part being flared 100 upwardly and outwardly away from the cord and thence downwardly on a radius equal to

at least twice the diameter of the cord, substantially as and for the purpose specified.

3. The combination of an electric - light socket having a flexible conductor secured thereto; a guard secured to said socket and surrounding said conductor, said guard being suitably flared and curved at its upper part to prevent said conductor from being abruptly bent near its junction with said socket, and 10 said guard being provided below the flared part with apertures to permit the escape of moisture, substantially as described.

4. A guard for flexible conductors, comprising a screw-threaded nipple lined with 15 insulating material and having secured thereto and in alignment therewith a member having a pocket extending below the upper end

of said nipple and having its upper part flared and curved outwardly substantially as shown and described.

5. A guard for flexible conductors, comprising a screw-threaded nipple, and a sheet-metal member secured thereto having its upper end flared outwardly and curved back upon itself and having at its lower end a 25 pocket below the level of the top of the nipple and provided with apertures, substantially as shown and described.

Signed at Chicago this 23d day of June, 1902.

GEORGE R. PIMLOTT.
